UNITED STATES PATENT OFFICE

2,582,414

RAILWAY VEHICLE UNDERFRAME AND COUPLER SUPPORT STRUCTURE

Allen W. Clarke, St. Charles, and William C. Krautheim, Pasadena Park, Mo.; said Krautheim assignor to General Steel Castings Corporation, Granite City, Ill., a corporation of Delaware, and said Clarke assignor to American Car and Foundry Company, New York, N. Y., a corporation of New Jersey

Application January 8, 1947, Serial No. 720,806

4 Claims. (CL 213—61)

1

The invention relates to railway vehicles and more particularly to railway vehicle underframe structure including a yielding coupler carrier and an associated rigid safety carrier.

One object of the invention is to simplify the construction and assembly of the yielding coupler carrier and associated structure and to facilitate the removal of the yielding carrier.

Another object is to provide for tilting the yielding carrier in a vertical plane extending transversely of the car and to avoid undue play between the parts.

Other detail objects will be apparent to those skilled in the art from the following description and accompanying drawings, in which:

Figure 1 is a top view and partial section on the line 1—1 of Figure 2 of a railway vehicle underframe structure including a coupler carrier constructed according to the invention.

Figure 2 is a transverse vertical section taken approximately on the line 2—2 of Figure 1, and

Figure 3 is a longitudinal vertical section taken approximately on the line 3—3 of Figure 1.

The vehicle platform 1 has a buffer sill 2 at its forward end and a substantially U-shaped safety support 3 for a coupler is integral with and depends from the buffer sill and includes side members 4 and 5 and a horizontal cross bar 6. The coupler includes a head 8 and a shank 9 which has its rear end attached to a draft gear (not shown) mounted on draft sills 10 integral with the platform.

Normally the coupler is supported by a yielding carrier 11 suspended near its ends by vertical bolts 12 which extend through springs 13 with the upper ends of the bolts provided with seats on the springs. The platform safety support side members 4 and 5 have rearwardly projecting integral brackets 14 seating springs 13.

Angular brackets 15 are attached rigidly to the safety carrier side members 4 and 5 by bolts 16 and extend rearwardly and inwardly of the members and form vertical guides 19. Each end of carrier 11 has a vertically extending arm 17 of channel cross section slidably receiving a bracket guide 19 to guide the carrier in its vertical movement. The bottoms 18 of channels 17 are curved vertically so that carrier 11 can tilt in a vertical plane transversely of the car, when the coupler swings toward an end of the carrier, without binding against guides 19. This arrangement tends to maintain extended line contact between a guide and adjacent carrier arm when the carrier shifts endwise and thereby reduces wear and play between the parts.

2

Each bracket 15 has a downwardly and inwardly projecting lug 20 underlying but spaced below carrier 11 and serving as a safety device in the event of failure of the corresponding spring 13.

5 The spring and bolt units 12, 13 supporting the floating carrier are readily applied to and removed from the platform casting, and the guide brackets 15 are similarly readily applied to and removed from the safety support side members 4, 5. The safety support cross bar 6 may be of any desired section and may be reinforced interiorly by suitable webs without regard to the presence and operation of the floating carrier.

10 15 The details of the construction may be varied substantially without departing from the spirit of the invention and the exclusive use of those modifications coming within the scope of the claims is contemplated.

20 What is claimed is:

1. In combination, a railway vehicle underframe end structure having draft sills and provided with rigid members forming a pocket for a coupler positioned between said sills and adapted to limit downward movement of such a coupler, brackets extending rearwardly of said pocket forming members spaced transversely of the structure and having substantially vertical guides facing toward each other and rearwardly of said pocket forming members, a coupler carrier extending transversely of and beneath said draft sills and having elements at each of its ends to slidably engage said guides, and means depending from said structure and yieldingly supporting said carrier.

35 2. In combination, a railway vehicle underframe end structure having draft sills and provided with rigid members forming a pocket for a coupler positioned between said sills and adapted to limit downward movement of such a coupler, brackets extending rearwardly of said pocket and spaced transversely of the structure and having substantially vertical guides facing toward each other, a coupler carrier extending transversely of and beneath said draft sills and having a vertically

40 45 50 extending channel at each of its ends slidably receiving a corresponding guide, means depending from said structure and yieldingly supporting said carrier, and elements rigid with said members and brackets and underlying said carrier to form a safety support therefor.

3. In combination, a railway vehicle underframe end structure having draft sills and provided with rigid members forming a pocket having spaced sides and a bottom for a coupler posi-

tioned between said draft sills and adapted to limit downward movement of such a coupler, brackets detachably secured to the members forming the sides of said pocket and extending rearwardly and inwardly therefrom to form substantially vertical guides facing toward each other, a coupler carrier extending transversely of and beneath said draft sills with its ends slideable vertically along said guides, means depending from said structure and yieldingly supporting said carrier, and lugs extending downwardly and inwardly from the lower ends of said brackets and underlying the ends of said carrier to form a safety support therefor in the event of failure of said means.

4. In combination, a railway vehicle under-frame device including integral elements forming a coupler receiving pocket with upright side members and a bottom member comprising a coupler safety support, a coupler carrier positioned rearwardly of said members and movable vertically relative thereto, a yielding mounting for said coupler carrier positioned rearwardly of said members, brackets secured to the pocket side members and extending rearwardly and inwardly

therefrom and cooperating with the ends of the coupler carrier to guide the same in its vertical movement, the ends of the coupler carrier being curved vertically to accommodate tilting of the carrier in a vertical plane extending transversely of the device.
